UNITED STATES PATENT OFFICE.

GEORGE H. HAZELTON, OF DETROIT, MICHIGAN.

DRIVING AND REVERSING CLUTCH.

1,191,594.

Specification of Letters Patent. Patented July 18, 1916.

Application filed September 22, 1915. Serial No. 51,938.

To all whom it may concern:

Be it known that I, GEORGE H. HAZELTON, citizen of the United States, residing at Detroit, county of Wayne, State of Michigan, have invented a certain new and useful Improvement in Driving and Reversing Clutches, and declare the following to be a full, clear, and exact description of the same, such as will enable others skilled in the art to which it pertains to make and use the same, reference being had to the accompanying drawings, which form a part of this specification.

My invention relates to an improvement in a driving and reversing clutch, designed more especially for use in connection with motor boats, though it may be employed in conjunction with hoisting apparatus, or in other installations where devices of this character are required.

One object of the invention is to provide an efficient driving and reversing clutch in which the driving shaft while rotating in one direction may be coupled with the propeller shaft of a boat (for example) to drive the latter forward, or to reverse the same as may be required.

In putting the invention into effect, a double annular cone is fitted to the driven or propeller shaft, which may be actuated in a "forward" direction by a slideable member keyed to the driving shaft engaging one of the annular cone portions, or in a reverse direction through a plurality of intermediate rolls forced into impinging relation with the other annular cone portions by the manual shifting of the slideable member in the reverse direction along the driving shaft.

Another feature of the invention consists in providing an adjustable locking device for the manually operated lever employed to shift the slideable member keyed to the engine shaft.

Other advantages and improvements will hereafter appear.

In the drawings accompanying this specification: Figure 1 is a horizontal sectional view through the clutch mechanism, taken on the parting line of the inclosing case, showing the mechanism coupled to provide a forward movement of the propeller blades (not shown). Fig. 2 is a similar view showing the rolls of the clutch mechanism forced into rolling driving contact with the double cone carried by the propeller shaft, thereby reversing the rotation of the propeller

blades. Fig. 3 is a fragmentary cross-sectional view on line 3-3 of Fig. 1. Fig. 4 is a fragmentary cross-sectional view on line 4-4 of Fig. 1, of a detail of construction. Fig. 5 is a side elevation of the device. Fig. 6 is a cross-sectional view on line 6-6 of Fig. 1. Fig. 7 is a cross-sectional view on line 7-7 of Fig. 2. Fig. 8 is a fragmentary view of the lever for manually operating the clutch mechanism, indicating the same locked in a neutral position. Fig. 9 is a like fragmentary elevation of the lever and locking mechanism as viewed from the opposite side, indicating the lever shifted and locked in its adjusted position.

Referring now to the letters of reference placed upon the drawings: A, indicates a driving shaft journaled at its forward end in a suitable bearing in the inclosing case B, divided horizontally and bolted together on a line with the driving shaft.

C, is a propeller shaft having a socket fitted with a bushing c, to receive the end of the driving shaft, which is reduced in diameter at one end that it may enter the end of the propeller shaft, as indicated in Fig. 1 of the drawings.

C', denotes a collar pinned to the propeller shaft, in turn bolted to a similar collar carried by the shaft of the propeller blades (not shown).

c', is a thrust bearing between the shoulder a, of the driving shaft, and the end of the propeller shaft, and c'', is a similar thrust bearing between the collar C', and the projecting hub b, of the bearing, in the inclosing case B, supporting the propeller shaft.

C'', is an annular cone tapering toward the propeller shaft C, having a screw-threaded engagement with the latter, its enlarged end being formed with a projecting flange C^a, to which is bolted the flange C^b, of an annular cone C³, tapering toward the driving shaft A.

D, is an annular slideable shaft sleeved on the driving shaft A, provided with a slot at d, for the passage of a key A', carried by the shaft A, the slot being of sufficient length to admit of a longitudinal movement of the annular shaft along the driving shaft;—the key however causing the shafts to rotate as a unit.

E, indicates a cone housed within the annular cone C'', having a projecting tapering hub E', screwed upon the end of the slideable shaft D, to reciprocate therewith.

F, denotes an adjustable annular frame or

cage sleeved over the tapering hub E', provided with a projecting collar F', extending into a supporting ring G. The ring G, is provided with ears g, through which project bolts g', for securing the ring to the lugs b', of the case B.

G', is a set screw carried by the ring to secure the collar F', to the latter, upon releasing which, the frame F, may be adjusted 10 to take up wear.

H, designates a plurality of rolls mounted on the shafts H', in turn loosely pinned to the annular frame F, the shafts being free to move along the pins h, in the slotted openings f, of the frame F, to provide for a slight radial adjustment of the rolls, whereby they may be forced into driving rolling contact with the annular cone C³.

h', are springs carried by the pins h, 20 adapted to force the rolls H, inwardly when released from driving engagement with the cone C³.

I, indicates a rocking, shifting lever, having trunnions I', journaled in a suitable bearing carried by the inclosing case B. Within the case B, the lever is forked, its slotted tines I², receiving the projecting lugs J', of a collar J, mounted upon the annular sliding shaft D, between the ball bearings K.

30 L, is a push rod supported in the lever I, having a projecting end L'.

M, denotes a pair of adjustable blocks fitted with bolts M', projecting through elongated slots n, in the quadrant-shaped 35 frame N, secured to the inclosing case B.

m, m, are lugs extending from the blocks M, M, with which the projecting end L', of the push rod engages to secure the lever following its manual adjustment.

40 L³, is a spring mounted upon the upper end of the push rod bearing against the enlarged ends L³, of the rod, and against a shoulder formed in the lever I, to receive the spring:—the purpose being to normally 45 maintain the projecting end L', of the rod in engaging relation with the lugs of the adjustable blocks M, M.

L⁴, is a keeper attached to the lever to secure the push-rod against displacement.

50 O, designates a collar pinned to the driving shaft to secure the shaft against lateral displacement.

Having indicated the several parts by reference letters, the construction and operation 55 of the device will be readily understood.

For purposes of description and to more clearly indicate the operation of the device, it is assumed to be employed in connection 60 with a motor boat (not shown). When it is the desire of the operator to drive the boat forward, the lever I, is manually operated forcing the cone E, into impinging relation with the annular cone C², (as indicated in Fig. 1 of the drawings) thereby rotating the 65 latter in the same direction as that taken

by the driving shaft A',—the lever being locked in its adjusted position by the projecting end L', of the push-rod L engaging the lug of the adjustable block M, as indicated in Fig. 9 of the drawings. It will 70 now be assumed that it is the desire of the operator to shift the clutch to a neutral position; i. e. the engine being permitted to run without operating the propeller blades. To accomplish this result, the operating lever 75 I, is given a slight movement to the left sufficient to release the cone E, from driving engagement with the annular cone C², the lever being locked in its neutral, or released position by lodging the projecting end L', 80 of the push-rod L, between the lugs m, m, of the adjustable blocks M, M,—as indicated in Fig. 8 of the drawings.

It will now be assumed that the operator desires to reverse the direction previously 85 taken by the propelling blades. This result is accomplished by a further movement of the operating lever I, to the left following the operation of the push-rod whereby it is released. This action causes the tapering 90 hub E', of the cone E, to move to the left sufficiently to force outwardly the rolls H, into impinging contact with the inner face of the annular cone C³. The rolls contacting throughout their length with the tapering 95 hub E', are rotated thereby in an opposite direction to that taken by the tapering hub and driving shaft A, while the annular cone C³, driven by the rolls through contact with its inner face, is revolved in the same direction as that taken by the rolls, and therefore in an opposite direction to that of the driving shaft; the rotation of the driven shaft C, being thus reversed to that of the driving shaft. If desired the lever I, may be locked 100 by the push-rod L, acting in conjunction with the adjustable blocks M, M, to secure the clutch mechanism in its "reverse" position in a similar manner to that previously explained relative to the "forward" and 110 "neutral" positions. It will be obvious that while the driving shaft operates in one direction only, the propeller shaft may be actuated in either direction, or remain at rest, as governed by the adjustment of the 115 manually operated controlling lever.

Having thus described my invention, what I claim is:—

1. In a device of the character described, a supporting frame, a driving shaft journaled therein, a driven shaft, a pair of annular cones tapering in opposite directions mounted upon the driven shaft and operating as a single unit therewith, an annular shaft slidable upon the driving shaft keyed 120 to rotate therewith, a cone carried by the annular shaft having a projecting, tapering hub and adapted to be forced into driving relation with one of the annular cones 125 of the driven shaft, a frame surrounding 130

- the tapering hub having radial slots to receive the shafts of a plurality of rolls, a plurality of rolls rotatable upon shafts projecting into the slots of the frame, transverse 5 pins for supporting said shafts in the slots of the frame, springs adapted to bear upon the shafts of the rolls to force them inwardly to the limit of their travel in the slots of said frame, and manually operated 10 means for shifting said annular shaft, whereby the tapering hub of the cone carried by the annular shaft is adapted to force said rolls outwardly and into impinging relation with the other annular cone.
- 15 2. In a device of the character described a supporting frame, a driving shaft journaled therein, a driven shaft, a pair of annular tapering cones provided with flanges at one end thereof, said flanges being bolted 20 together to form a single unit, the annular cones tapering respectively in opposite direction and carried by the driven shaft to rotate as a unit therewith, an annular shaft
- sleeved on a driving shaft, keyed to rotate therewith, but free to slide thereon, an annular ring carried by the annular shaft having a tapering, projecting hub and an annular flange extending from its periphery and tapering in a direction opposite to the hub, and adapted to engage one of the annular cones, a suitable frame surrounding the tapering hub to support a plurality of rolls, a plurality of rolls supported in the frame and adapted to be forced into contact with the other annular cone by the tapering 35 hub upon the manual adjustment of the annular shaft and manually operated means for longitudinally shifting said annular shaft with reference to the driving shaft.

In testimony whereof, I sign this specification in the presence of two witnesses.

GEORGE H. HAZELTON.
